UNITED STATES PATENT OFFICE.

IRWIN M. KROHN, OF CINCINNATI, OHIO.

DESIGN FOR A SHOE.

SPECIFICATION forming part of Design No. 33,990, dated January 29, 1901.

Application filed November 14, 1900. Serial No. 36,531. Term of patent 7 years.

To all whom it may concern:

(Be it known that I, IRWIN M. KROHN, a citizen of the United States, residing at Cincinnati, in the county of Hamilton and State of Ohio, have invented and produced a new and original Design for a Shoe, of which the following is a specification.

My invention relates to an original design for a shoe, of which the following is a description, reference being had to the accompanying drawings, making a part of this specification, in which—

Figure 1 is a side elevation of a shoe, showing the features of my design. Fig. 2 is a top plan view of Fig. 1.

The leading feature of my design is the configuration of the top of a shoe. The effect is produced by the contour and marginal lines which constitute the top of the shoe.

20 A represents the vamp, the top edge of which is formed of two incurving lines increasing to a semicircular shape over the instep.

B represents the instep-piece, the front of which is semicircular, extending in curved or undulating lines and terminating under the top.

D D represent marginal pieces forming the extension of the instep, the rear edge having gracefully - curved lines. C represents the 30 top, which is of plain form and without fac-
ing-pieces. Its lower edge is formed of curved lines joining the rear portion of the vamp to the quarters E, the top edge of which is of 35 curved form, whose upper marginal lines are curved and fit the similar curved lines of the top.

d represents the front marginal edges of the top. These edges have a graceful curve 40 inswelling from the front.

E represents the quarters, and F the toe-piece.

What I claim is—

The design for a shoe substantially as herein shown and described. 45

In testimony whereof I have hereunto set my hand.

IRWIN M. KROHN.
